UNITED STATES PATENT OFFICE.

HERBERT L. CURRIER, OF LYNN, MASSACHUSETTS, ASSIGNOR TO HIMSELF
AND ALBERT H. BREED, OF SAME PLACE.

PUSH-BUTTON.

SPECIFICATION forming part of Letters Patent No. 404,033, dated May 28, 1889.

Application filed July 12, 1888. Serial No. 279,699. (No model.)

To all whom it may concern:

Be it known that I, HERBERT L. CURRIER, of Lynn, in the county of Essex, State of Massachusetts, have invented a certain new and useful Improvement in Push-Buttons, of which the following is a description sufficiently full, clear, and exact to enable any person skilled in the art or science to which said invention appertains to make and use the same, reference being had to the accompanying drawings, forming part of this specification, in which—

Figure 1 is a side elevation of a push-button of the ordinary construction, a portion of the cap being broken away to show the interior; Fig. 2, a top plan view of my improved button, the cap being broken away to show the interior and the button proper removed; Fig. 3, a sectional view on line $\alpha\alpha$ in Fig. 2; and Figs. 4, 5, and 6, enlarged views showing certain details of construction.

Like letters and figures of reference indicate corresponding parts in the different figures of the drawings.

My invention relates to that class of push-buttons which are employed in connection with annunciators, electric bells, &c.; and it consists in certain novel features, as herein-after fully set forth and claimed, the object being to produce a simpler and more effective device of this character than is now in ordinary use.

The nature and operation of the improvement will be readily understood by all conversant with such matters from the following explanation.

In the drawings, A represents the body of the button; B, the cap, and C the button proper.

The body A is cylindrical in form and exteriorly screw-threaded, being provided at the base with an annular flange, b, and preferably composed of wood.

The cap B is provided with an interiorly screw-threaded socket which is deeper or higher than said body on which it is disposed, thus leaving a chamber, v, between the body and cap. A metallic plate, f, is secured by screws d to the top of the body A within said

chamber, a flat curved metallic spring, i, being also secured by one end to said body by means of screws g.

The button proper, C, consists of a cylindrical porcelain bolt, which passes through a central opening in the cap B and rests on the free end 15 of the spring i in such a manner that when said button is pressed inward the spring i will be forced into contact with the plate f.

In push-buttons as ordinarily constructed the conducting-wires D II, leading to different poles of the battery, are cut or broken at the button, and the two ends of the wire D thus formed are forced upward through a vertical opening in the body A and coiled 65 around the heads of the screws g in contact with the spring i, the ends of the wire H being secured in the same manner on the screws d in contact with the plates f, as shown in Fig. 1. This method necessitates the expenditure of much time and labor in attaching the button to the wires, and the break in the wires causes a loss of electricity and 70 interrupts the current. To obviate these objections, I form a circular groove or chamber, h, 75 (see Fig. 3,) on the under side of the body A. A screw, 25, preferably composed of brass, is then inserted in the body A through the spring i, and a similar screw through the plate f, said screw being of sufficient length 80 to project into the chamber h.

The screws 25 are provided at their lower ends with a hole, 35, and a lateral slit, 36, opening into said hole. The hook thus formed at the lower end of the screw is entirely 85 within the circumference of the body of the screw, so that the latter may be screwed through the insulated block or body A.

In the use of my improvement in attaching the push-button to the wires the screw 90 25 is turned out or back a small distance and the wire inserted in the hook 35, after which the screw is turned again until its head is in contact with the spring i or plate f, as the case may be. This causes a loop or twist to 95 be formed in the wire, as shown in Figs. 4 and 5, which fastens it securely to said screw, the chamber h affording room for said loop and

avoiding the necessity of having the points of the screws project beyond the bottom of the body A.

It will be seen that by the use of my improvement the push-button can be quickly attached to the wires and the necessity for cutting the wires for this purpose entirely obviated.

Having thus explained my invention, what I claim is—

1. The combination of an insulating block or body provided with a recess or chamber in its under side, a metallic plate on the upper side of said body, a metallic spring, also on the upper side thereof, a cap surrounding said body, a push-button in said cap for forcing said spring into contact with the plate, and screws passing through said plate and spring, respectively, and through said body

into the chamber in the under side thereof, 20 said screws being provided with hooks at their lower ends within said chamber for the conducting-wires.

2. The combination of an insulating block or body, a metallic plate on the upper side 25 thereof, a metallic spring, also on the upper side thereof, a cap surrounding said body, a push button in said cap for forcing said spring into contact with the plate, and screws passing through said plate and spring, re- 30 spectively, and through said body, said screws being provided at their lower ends with hooks which are entirely within the circumference of said body.

HERBERT L. CURRIER.
